PATENTED MAY 21, 1907.

N. SMITH.

WRENCH.

APPLICATION FILED FEB. 4, 1907.

Fig. 7.

2 SHEETS—SHEET 1.

Fig. 3.

A technical line drawing of a belt and buckle assembly. The belt features a central strap with a textured surface and two leather-like side panels. A metal buckle is attached to the right side panel. The buckle has a rectangular frame with a central rectangular plate and a circular fastening element. The drawing is annotated with various numbers: 11a, 11, 12, 13, 10, 11b, 13, 13a, 13b, 15, 15a, 147, and 148. The numbers 11a, 11, 12, 13, 10, 11b, 13, 13a, 13b, 15, 15a, and 147 are distributed along the belt and buckle, while 148 is located near the bottom left.

UNITED STATES PATENT OFFICE.

NATHAN SMITH, OF STEVENVILLE, MARYLAND.

WRENCH.

No. 854,248.

Specification of Letters Patent.

Patented May 21, 1907.

Application filed February 4, 1907. Serial No. 355,613.

To all whom it may concern:

Be it known that I, NATHAN SMITH, a citizen of the United States, residing at Stevensville, in the county of Queen Anne and State 5 of Maryland, have invented certain new and useful Improvements in Wrenches; and I do hereby declare the following to be a full, clear, and exact description of the invention, such as will enable others skilled in the art to 10 which it appertains to make and use the same.

My invention relates to new and useful improvements in wrenches and more particularly to that class adapted to be used for holding pipes, bolts and similar objects having oblong circular bodies and also for turning nuts and the like, and my object is to provide means for readily and quickly adjusting the movable jaw to regulate the space between the movable and fixed jaws to fit various sized objects.

A further object is to provide means for holding the movable jaw in its adjusted position.

A still further object is to provide resilient 25 means for directing the movable jaw into firm engagement with the object disposed between the movable and fixed jaws and a still further object is to provide means for securing and positively holding the parts of 30 the wrench in their adjusted position.

Other objects and advantages will be hereinafter referred to and more particularly pointed out in the claims.

In the accompanying drawings which are 35 made a part of this application, Figure 1 is a perspective view of my improved form of wrench showing the same in its opened position. Fig. 2 is a side elevation thereof showing the parts of the wrench in their adjusted 40 position in full lines and in their opened position by dotted lines. Fig. 3 is a perspective view of the resilient adjusting mechanism removed from the wrench. Fig. 4 is a side elevation partly in section of a wrench showing 45 a slightly modified form of resilient adjusting mechanism. Fig. 5 is an elevation partly in section of a slightly different form of wrench and showing parts thereof in position to be adjusted, and, Fig. 6 is a perspective view of 50 the modified form of resilient adjusting mechanism removed from the wrench.

Referring to the drawings in which similar reference numerals designate corresponding parts throughout the several views, 1 indicates the main shank of my improved form

of wrench, the upper end of which is provided with a fixed jaw 2 while the extreme lower end thereof is tapered and provided with a notch 3 which is adapted to be used for various purposes such as extracting nails or the like. Slidably mounted upon the shank 1 is a movable jaw 4 which is provided at one end with a socket 5 through which the shank 1 is disposed, said socket being of proper dimensions to snugly fit the shank.

In Figs. 1 and 2 of the drawings I have shown the jaws 2 and 4 provided with a plurality of serrations or teeth 6, said teeth being upon the meeting edges thereof which are adapted to be employed for engaging bodies having round surfaces while in Fig. 4 of the drawings I have shown the meeting faces of the jaws as smooth so that the same may be employed upon objects having square or flattened surfaces.

Extending inwardly from the lower edge of the movable jaw 4 is a slot 7, the contour of the upper surface of said slot being slightly curved to receive the curved end of an auxiliary shank 8, said shank being pivotally secured within the slot 7 by disposing a rivet 9 through the jaw 4 and upper end of the auxiliary shank 8, the curved end of the auxiliary shank being so arranged that when the auxiliary shank is directed inwardly to hold the 85 movable jaw into engagement with an object, the curved end will engage the curved surface of the slot 7 and direct pressure thereagainst.

The lower end of the auxiliary shank is 90 preferably flattened or wedge shaped so that the same may be used as a screwdriver when desired.

In order to hold the movable jaw in its adjusted position, I provide the inner edge of 95 the shank 1 with a plurality of ledges 10, the bearing surfaces of which are semicircular in cross section with which is adapted to engage a resilient latch 11, said latch being secured to the auxiliary shank 8 in such a manner 100 that when the auxiliary shank is closed or directed into engagement with the main shank 1, the jaw 4 will be moved into firm engagement with the object between the jaws and held in this position under pressure and 105 by forming the bearing surface of the ledges semicircular a lip 10^a is formed at the outer edge thereof so that the engaging end of the latch will be held against casual displacement from the ledge with which it is engaged.

110

The latch 11 is preferably formed of a single section of resilient wire, and formed in the shape of a hollow square, the lower horizontal section 11^a being adapted to engage the ledges 10 while the upper horizontal section 5 forms a bearing 11^b which is directed through a bore in the auxiliary shank 8 to form a pivotal bearing and extends a sufficient distance through the shank to form a support for a coiled section 12, said coiled section terminating in an arm 13, the extreme outer end 13^a of which is looped around the auxiliary shank 8 to hold said arm substantially parallel with the shank and give tension to 10 the latch when the auxiliary shank is closed. By this construction it will be seen that when the latch is into engagement with one of the ledges 10 and the auxiliary shank 8 is moved inwardly, the latch will pivot in the auxiliary shank and the coiled section 12 and arm 13 direct the latch against the contracted ledge under tension and cause the jaw 4 to move toward the fixed jaw 2 and into positive engagement with the object upon which the wrench is being employed and holding the auxiliary shank in its closed position, the coiled section 12 and arm 13 will continuously direct pressure against the movable jaw until such time as the auxiliary shank is released. By using this construction of latch I am also enabled to dispense with the springs commonly employed in connection with the movable jaws of wrenches of this class to allow the same to slightly yield when a reverse movement is given the wrench as the resiliency of the latch will permit the movable jaw to yield slightly when the wrench is given a reverse rotation to obtain a new bite on the object being turned.

40 In Fig. 2 of the drawing I have shown the opened position of the auxiliary shank in dotted lines and the closed position of said shank in full lines and it will be seen that when the auxiliary shank is moved inwardly toward the main shank that the tension on the latch will cause the auxiliary shank and movable jaw secured thereto to move upwardly under pressure, the movement of the several parts coincident to the tension exerted by the 45 coiled section 12 being clearly disclosed by dotted and full lines in said figure.

When applying the wrench into engagement with an object the auxiliary shank is moved outwardly a sufficient distance to disengage the lower bar 11^a of the latch 11 from the ledges 10 when the jaw may be moved upwardly or downwardly to engage an object placed between the movable and fixed jaws and after the movable jaw has been 50 casually moved into engagement with the object the same may be firmly clamped thereon by moving the auxiliary shank into engagement with the main shank, the tension of the latch and arm secured thereto being 55 sufficient to positively fix the teeth on the

movable and fixed jaws into engagement with the object and the auxiliary shank may be positively held into engagement with the fixed shank by means of a substantially L-shaped keeper 14, the main stem of which is 70 passed through an opening 15 in the fixed shank 1 and is adapted to move longitudinally therethrough so that when the shanks are brought together the extension 15^a of the keeper 14 may be directed over the auxiliary shank 8 and positively hold the same in its closed position until such time as it is desired to release the wrench from the object. The keeper also serves to limit the outward movement of the jaw 4 so that the same will 75 not move entirely from off the shank 1.

In Figs. 4, 5 and 6 of the drawings I have provided a slightly modified form of latch and in this instance I preferably form the latch 16 of a flat strip of spring metal, one 80 end of which is seated in a depression 17 in the inner face of the auxiliary shank 8 and is secured thereto in any preferred manner as by rivets 18 which are directed through the end of the latch and the adjacent portion of 85 the auxiliary shank 8. The free end 16^a of the latch 16 is curved outwardly from the inner face of the shank 8 and is adapted to engage the ledges 10 in the shank 1 and that portion of the latch between the fixed and 90 free end is bent outwardly to form a shoulder 19 against which the auxiliary shank 8 is adapted to impinge when said shank is in juxtaposition to the main shank 1 thereby causing the latch 16 to exert additional upward pressure 95 on the auxiliary shank 8 and movable jaw 4, the latch 16 being substantially straight throughout its length when the auxiliary shank is closed, the pressure upon the shoulder 19 also serving to hold the free end 16^a 100 firmly into engagement with the ledges 10.

It will now be seen that I have provided a very cheap and economical form of wrench and one that may be used for turning pipes or other objects having round surfaces or 105 nuts and like objects having flat surfaces. It will further be seen that I have provided means for quickly adjusting the jaws of the wrench to fit various sized objects and also for quickly and positively directing the jaws 110 into engagement with the object.

What I claim is:

1. In a wrench the combination with a shank having a fixed jaw, a movable jaw on said shank and an auxiliary shank for said movable jaw; of a latch on one shank adapted to engage the opposite shank and direct the movable jaw toward the fixed jaw said latch being yieldable between its two ends.

2. In a wrench the combination with a 125 shank having a fixed jaw, a movable jaw slidably mounted on said shank, an auxiliary shank pivotally secured to said movable jaw and resilient means on the auxiliary shank adapted to engage the opposite shank and 130

direct the movable jaw toward the fixed jaw said means being yieldable between its two ends.

3. In a wrench the combination with a shank having a fixed jaw at one end, a movable jaw slidably mounted on said shank, said jaws having teeth thereon, an auxiliary shank pivotally secured to the movable jaw, a resilient latch carried by the auxiliary shank and adapted to engage the opposite shank said latch being yieldable between its two ends and an arm adapted to hold said latch under tension.

4. In a wrench the combination with a shank, a jaw at one end of said shank, a plurality of ledges in one edge of said shank, the bearing faces of which are semicircular, a movable jaw having a slot therein slidably mounted on said shank, said jaws having teeth on their meeting edges, an auxiliary shank having a curved upper end adapted to enter said slot, means to pivotally secure said auxiliary shank to the movable jaw, a latch carried by said auxiliary shank one end of which is directed through the auxiliary shank to form a pivot point for the latch while the opposite end thereof is adapted to

engage the ledges on the main shank, a coiled section at the upper end of said latch, an arm extending from said coiled section and means to secure the free end of said arm to the auxiliary shank, said latch, coiled section and arm being formed of a continuous section of material.

5. In a wrench the combination with a shank having a fixed jaw at one end thereof; of a movable jaw on said shank, an auxiliary shank pivotally secured to said movable jaw, a resilient latch carried by said auxiliary shank and adapted to engage the main shank said latch being yieldable between its two ends; means to direct tension on said latch and a keeper carried by the main shank adapted to engage the auxiliary shank and hold the same in juxtaposition to the main shank.

In testimony whereof I have signed my name to this specification in the presence of two subscribing witnesses.

NATHAN SMITH.
